UNITED STATES PATENT OFFICE

170,167

GRAVY BOAT OR THE LIKE

Martin Rosen, Flushing, N. Y.

Application March 4, 1953, Serial No. 23,877

Term of patent 14 years

(Cl. D44—15)

To all whom it may concern:

Be it known that I, Martin Rosen, a citizen of the United States, residing at 75—12 195th Street, Flushing, State of New York, have invented a new, original, and ornamental Design for a Gravy Boat or the like, of which the following is a specification, reference being had to the accompanying drawing, forming a part hereof.

Fig. 1 is a side elevational view of a gravy boat or the like showing my new design.

Fig. 2 is a top plan view of the gravy boat of Fig. 1.

Fig. 3 is a front elevational view of the gravy boat of Figs. 1 and 2.

I claim:

The ornamental design for a gravy boat or the like, as shown.

MARTIN ROSEN.
